(57) **CLAIM**

The ornamental design for a table base, as shown and described.

DESCRIPTION

FIG. 1 is a perspective view of a table base shown with a console table top in accordance with the new design; FIG. 2 is a top view thereof; FIG. 3 is a front elevational view; a rear elevational view being a mirror image thereof; FIG. 4 is a right side elevational view; a left side elevational view being a mirror image thereof; FIG. 5 is a perspective view of an alternative embodiment of the table base shown with a square end table top in accordance with the new design; and, FIG. 6 is a perspective view of an alternative embodiment of the table base shown with a square coffee table top. The broken lines in the figures are for illustrative purposes only and form no part of the claimed invention.
